COKE OVEN DOOR MACHINE

Olav M. Tweit, Mountain Lakes, N. J., assignor
to Allied Chemical & Dye Corporation, New
York, N. Y., a corporation of New York

Application July 11, 1950, Serial No. 173,141

25 Claims. (Cl. 212—4)

1

This invention relates to door machinery, and is particularly concerned with apparatus for operating "self-sealing" doors of the type employed to form the removable end closures for horizontal coking chambers of coke ovens of the type commonly used in the manufacture of metallurgical coke.

As used with horizontal coke ovens, "self-sealing" doors comprise a refractory plug projecting into the coking chamber and a metal sealing member at the outer side of the plug which is pressed into contact with the metal surface of the door frame of the coking chamber when the door is in place to seal the door opening. Coke oven doors of the type referred to are heavy structures and must be anchored securely in place in their normal closed position to prevent gas leakage through the joints between the doors and cooperating door frames. It is now standard practice to secure a coke oven door of this type in place by the use of one or more, usually two, latch bars acting between a rigid metal outer portion of the door, and stationary hook parts located at the sides of the door and carried by a metallic door frame member or other portion of the metallic armor at the sides of the coke oven battery and in normally fixed relation with the coke oven brickwork. One type of latch bar is pivotally connected to the door by a rotatable member in the form of a spindle or jackscrew adapted to rotate about a horizontal axis for turning movement from a horizontal position in which the latch bar engages the cooperating stationary hooks on the door frame, into an inclined position in which the latch bar is disengaged from the hooks. The door also comprises hook plates arranged to engage cooperating hooks on a door machine for grasping the door and manipulating it during its removal from the coke oven mouth for cleaning purposes.

The door machine generally employed for removing and replacing the above-described type of coke oven door comprises means, in the form of wrenches, for loosening and tightening the spindles or jackscrews on the door, means for rotating the latch bars thereof into and out of engagement with the door frame hooks, and hook means for engagement of the hook plates of the door to lift the door and hold it firmly suspended in retracted position from the coke oven mouth. As of the present, the door machines for operating this assembly generally involve the employment of three separate motors or actuating mechanisms with a plurality of controls for individually operating the wrenches, latch bar rotating means and movable hooks of the apparatus. This

2

necessitates the use of considerable equipment and represents a substantial expense. Hence, provision of a simpler less expensive arrangement for coordinating the operation of, and actuating the foregoing door machine elements in proper sequence has assumed considerable interest in the industry. Further, in tightening the rotatable members or spindles of a coke oven door during replacement thereof using conventional door machine apparatus, it often develops that one spindle may be tightened more than the other, resulting in an insecure non-gas tight closure between portions of the door and the door frame with consequent gas leakage. Hence, simple easily operated means associated with the door machine for applying equal tightening force to the door spindles has also been sought after, along with suitable socket wrench mechanism in combination with such means for readily and quickly engaging the spindles of a coke oven door even if such spindles are out of alignment due to unevenness of the tracks on which the door machine is propelled along the battery face, play of the door hooks and hook plates in their respective positions on the door machine and the door, small inequalities resulting from uneven expansion of the brickwork of the coke oven battery and the like.

One object of the invention is to provide door machinery of simple and rugged construction to remove and replace jackscrew type coke oven doors, including a single power means in association with other suitable means, for coordinating and performing the operations of loosening or tightening the jackscrews or spindles of the door, rotating the latch bars thereof into or out of engagement with the frame hooks and engaging or disengaging the hooks from the hook plates on the door, in proper sequence to remove or replace the door. Another object is to provide a door machine having means for applying equal tightening force or torque on the spindles of the door. Another aim of my invention is to afford means located on the door machine for offsetting misalignment between the wrenches on the door machine and the spindles on the door, and means for effecting substantially instant engagement between such wrenches and spindles.

Other objects and advantages of the invention will appear hereinafter.

The door machine of my invention comprises first of all a novel and improved self-aligning socket wrench mechanism for engaging and turning the rotatable members (spindles or jackscrews) of a coke oven door even if the socket

wrenches and associated rotatable members are out of alignment, including a driven shaft, a flared end portion for engaging the rotatable members, a spring mounted at one end in a hollow portion of such shaft and having its other end associated with the flared portion, and a sleeve connecting the driven shaft with the flared portion for rotation thereof, the flared portion being angularly movable with respect to the sleeve and the latter being angularly movable with respect to the shaft. Another feature of the invention device constitutes rack and pinion means comprising two racks each in contact with a single pinion and each in respective engagement with a system of gears arranged to cause rotation of the socket wrenches and adapted to exert equal tightening force on the wrenches and rotatable members, during replacement of a door in its frame and tightening of the latch bars in the hook members. A clutch mechanism is provided in conjunction with the foregoing system of gears to allow a measure of play between movement of the rack and pinion means and the thus actuated wrenches and rotatable members, for reasons hereinafter pointed out.

My improved door machine also includes members in the form of fingers for rotating the latch bars of the door into and out of engagement with the hook members on the door frame, hooks for engaging the hook plates of the door and a cam operated member interconnected with the fingers and hooks, the hooks and related structure being preferably designed so that the coke oven door moves upward a short distance against its door frame just prior to retraction of the door from the coke oven mouth, and moves downward against the frame and into its seat just after the door makes contact with its frame during replacement of the door. A spring pressed member is provided which is adapted to urge the lower portion of the door machine against the lower portion of the door whereby, when the door machine and an engaged door are suspended out of contact with the coke oven mouth, the machine and door are in a plane somewhat inclined from the vertical with the lower portion of the machine and door farther forward than the upper portion thereof.

An important feature of the invention resides in provision of a single, preferably hydraulic, actuating means associated with the rack and pinion means and the cam operated member, for automatically coordinating the operation thereof, whereby on actuation of the hydraulic means in one direction to remove a coke oven door, the rotatable members thereon rotate in a direction to disengage the latch bars from the hook members of the door frame, the hooks engage the hook plates of the door and the fingers rotate the latch bars out of the hook members, and the opposite sequence of operations takes place on actuation of the hydraulic means in the opposite direction to replace the door against its door frame.

The door machine of these improvements is supported and balanced on a carrier adapted to retract the machine and an engaged coke oven door away from the coke oven mouth for cleaning and to advance the machine and door toward the mouth of the coke oven for replacement of the door against its frame. A mechanism is further afforded for properly adjusting the position of the door machine and the socket wrenches thereof relative to the rotatable mem-

bers on the door, such function being principally in the nature of a fine adjustment.

In the accompanying drawings forming a part of this specification and showing for purposes of exemplification a preferred apparatus in which the invention may be embodied and practiced but without limiting the invention specifically to such illustrative instances:

Figure 1 is a side elevation of the door machine of the invention in operative relationship with a coke oven door;

Figure 2 is a front elevation of a type of coke oven door adapted to be handled by the door machine of the invention;

Figure 3 is an enlarged vertical section through the door machine shown in Figure 1;

Figure 4 is a plan view of the door machine and coke oven door of Figure 1 shown partly in section through the upper door fastening mechanism;

Figure 5 is a section taken along line 5-5 of Figure 3;

Figure 6 is a section taken along line 6-6 of Figure 3;

Figure 7 is an enlarged detail of the upper socket wrench mechanism and associated gear system shown in Figure 3;

Figure 8 is a section taken along line 8-8 of Figure 7;

Figure 9 is a section taken along line 9-9 of Figure 7;

Figure 10 is a section taken along line 10-10 of Figure 7; and

Figure 11 is a schematic representation illustrating certain details in connection with the operation of the door machine of the invention.

In Figure 1 there is shown in vertical section a door machine 15 positioned at one end of a horizontal coking chamber 16 forming one of a series of laterally adjacent chambers of a coke oven battery, a door frame 17 at the mouth of the chamber 16, and a "self-sealing" door 18 comprising a refractory plug 19 and a metal sealing edge 20 extending around the entire periphery of the door and adapted to be pressed into contact with the door frame 17. The door 18 (see also Figures 2 and 4) is supported in sealing relation to the coking chamber by a pair of upper and lower latch bars 23 rotatably mounted on the door 18 on spindles or jackscrews 24 which are formed with squared heads 25 and with threaded portions 26 cooperating with threaded brackets 27 on the door assembly so that the bars can be moved perpendicularly of the door by rotating the jackscrews 24. Door frame 17 at the mouth of the coking chamber 16 is fitted with hooks 30 which are adapted to engage the latch bars 23 when they are rotated to the horizontal position. By turning the jackscrews 24 in one direction, the latch bars 23 are forced away from the door 18 and pressed against the hooks 30 to hold the door against the door frame. By turning the jackscrews in the other direction, the latch bars 23 are rotated out of engagement with the hooks 30 to permit removal of the door. The door 18 is provided with upper and lower hook plates 33 and with bosses 34. Bumpers 35 on the door machine cooperate with bosses 34 to hold the door erect during manipulation.

The door machine 15 is encased in a housing 38 which is entirely suspended from a lever or yoke 39 by means of pivot pins 40, brackets 44 (see Figure 6) connected to pivot pins 40 and housing 38 providing reinforcement for securely maintaining the housing in suspension without

oscillation or swaying thereof. A ram or carrier 41 connected to yoke 39 by pins 42 supports the entire door machine and associated housing. Ram 41 in turn is carried by a support 43 and is arranged thereon to be retracted away from and advanced toward a coke oven door by suitable means (not shown). Pivottally connected at point 48 to yoke 39 is a turnbuckle 46, the lower end of which is fastened at point 45 to a bracket 47 rigidly attached to door machine housing 38. Expansion of turnbuckle 46 raises closed end 49 of lever 39 and causes the lever to rotate in a clockwise direction about pivot pin 42 to thereby raise the entire housing 38 and enclosed door machine.

15 When turnbuckle 46 is contracted, the closed end 49 of lever 39 is lowered, resulting in counterclockwise rotation of lever 39 about pivot pin 42 and thereby lowering the housing 38 and the enclosed door machine mechanism. It will be apparent that the foregoing turnbuckle means for lowering and raising the door machine, as hereinafter more fully described, permits a fine adjustment of the door machine and socket wrenches (hereinafter to be described) thereof in relation to the door and jackscrews 24 thereon, for more convenient manipulation of the coke oven door.

As more clearly seen in Figure 7, the door machine 15 of the invention includes upper and lower parallel self-aligning socket wrench mechanisms 50 of novel construction, comprising flared socket wrenches 52, each adapted to fit over the square end 25 of a jackscrew 24. Each socket wrench 52 has rounded outwardly extending side portions 51 and an end closure member 58. Side portions 51 are in frictional contact with the inner surface of one end 53' of a sleeve 53 retained by housing 55, the inner surface of the opposite end 53" of the sleeve being in frictional engagement with the surface of a metal block 57 having rounded outwardly extending side portions; the block being keyed to the end of a driven shaft 54. In this arrangement sleeve 53 is non-rotatable with respect to shaft 54 and socket wrench 52, and the sleeve and wrench accordingly rotate in unison with the shaft. However, sleeve 53 may move angularly with respect to shaft 54 over the rounded convex surface of member 57, and socket wrench 52 may move angularly with respect to sleeve 53 through contact of the end 53" of the sleeve with the similarly rounded outer side portions 51 of the socket wrench. It is apparent then that this sleeve arrangement connecting driven shaft 54 with socket wrench 52 permits both longitudinal and lateral movement of the socket wrench in relation to a corresponding jackscrew. Mounted in a hollow end portion 59 of shaft 54 is a compression spring 60, the opposite end of which is in contact with the end closure member 58 of socket wrench 52.

When the socket wrench is in free position out of contact with a jackscrew, spring 60 urges sleeve 53 and socket wrench 52 forward until shoulder *a* at end 53" of sleeve 53 makes contact with shoulder *b* of housing 55, and shoulder *c* at end 53' of sleeve 53 is in engagement with shoulder *d* of end closure member 58 of socket wrench 52. In this position socket wrench 52 is maintained substantially perpendicular to the face of a coke oven door prior to engagement thereof. When socket wrench 52 is in operative engagement with the square end 25 of a jackscrew, as illustrated in Figure 7, the force against the spring generally causes it to contract moving sleeve 53 back and breaking contact between

shoulder *a* of the sleeve and shoulder *b* of housing 55. Usually, such force also brings about disengagement of shoulder *c* of sleeve 53 and shoulder *d* of end closure member 58. Under these circumstances, socket wrench 52 is free to move longitudinally or laterally in order to fully engage the jackscrew. The foregoing socket wrench structure is thus designed to absorb any sudden shock of contact between the wrench and a jackscrew, and is also such that the wrench will adjust itself to properly engage and coact with a corresponding jackscrew even if the socket wrench and jackscrew are not in perfect alignment.

Driven shaft 54 has a gear 61 fixed thereon near the end opposite the hollow portion of the shaft, the latter being mounted in bearings 62 retained in a housing 63. Meshing with gear 61 is a larger gear 64 loosely mounted on a driving shaft 65 disposed parallel to shaft 54. As seen particularly in Figure 10, shaft 65 has a series of equally spaced jaws 66 thereon mounted to fit within a series of similar equally spaced jaws 67 located on gear 64. The space between the adjacent jaws 66 and 67 provides a clutch mechanism allowing about 20 degrees of rotation between shaft 65 and gear 64. However, the difference in size between gear 64 and gear 61 on driven shaft 54 is such that the amount of free rotation between driving shaft 65 and driven shaft 54 and the associated socket wrench 52, is about 50 degrees. Mounted on the opposite end of shaft 65 from gear 64 is another gear 70 having teeth 69 and a flat portion 78 (Fig. 6). Shaft 65 and gears 64 and 70 are mounted on bearings 71 arranged in housing 63 which is composed of two portions 72 and 73 fastened together by means of bolts 74. The housing 63 is supported by a base plate 75 which is secured by means of bolts 80 to a plate 76 connected to door machine housing 38.

As more clearly seen in Figure 3, the upper and lower socket wrench mechanisms are composed of the same structural elements designated by like reference numbers except that in the lower mechanism an idler 89 is included in engagement with gears 61 and 64 to give the same directional rotation to both the upper and lower socket wrenches 52.

Referring particularly to Figure 6, a pair of parallel segmental racks 77 located one above the other are provided, each of these racks having teeth containing end segments 77a and 77b and each of segments 77a containing an adjacent flat portion 79. Teeth 81 of end segments 77a are adapted for operative engagement with teeth 69 of gears 70, and flat portions 79 of rack segments 77a are arranged to cooperate with flat portions 78 of gears 70. End segments 77a of racks 77 are each mounted to slide in a rack housing 83 constituting an extended portion of housing 63 while the respective opposite end segments 77b closely adjacent each other are mounted to slide in a common housing 84. Within housing 84, teeth 85 of each of rack segments 77b are in contact with the teeth 90 of a pinion 86 mounted to rotate about pin 87 (see also Figure 3). A pair of compression springs 88 are positioned in housing 84 in contact with end segments 77b of racks 77 urging them away and tending to maintain the racks in a centered position with respect to each other.

Rack housing 84 along with racks 77 and pinion 86 is reciprocated back and forth in a vertical direction by means of a hydraulically driven pis-

ton 91 (see Figure 3) contained in a cylinder 92 and attached to a piston rod 93 having sliding engagement with a bearing 100. The opposite end of piston rod 93 is connected to a cross head 95 comprising members 96 which are arranged to slide in guideways 97 of a plate 98 attached to door machine housing 38 by means of bolts 99. Referring now chiefly to Figure 5, a pair of arms 102 connected to cross head 95 and fitting through slots 101 in rack and pinion housing 84, have a rectangular cam member 103 attached to their opposite ends by means of bolts 104.

On initial actuation of piston 91 in a downward direction, cross head 95 carries housing 84, enclosed pinion 86 and both racks 77 simultaneously in the same direction, such movement causing rotation of both the upper and lower socket wrenches and associated jackscrews in a direction to allow disengagement of latch bars 23 from the frame hooks 30. Rotation of the jackscrews ceases when flat portions 79 of rack segments 77a make contact with flat portions 78 of gears 79 in the position shown in Figure 6. Actuation of the piston 91 in an upward direction from the position shown in Figure 6, brings about movement of both racks 77, along with housing 84 and pinion 86 simultaneously in the same direction to cause rotation of the socket wrenches and jackscrews in a direction to tighten the jackscrews through contact of teeth 81 of rack segments 77a with teeth 78 of gears 79. During such movement, pinion 86 within housing 84 remains stationary with respect to racks 77 until one of them, say the upper rack, stops moving due to complete tightening of the upper jackscrew. Under these circumstances continued upward movement of the piston causes pinion 86 to rotate with respect to the racks and act as a differential to permit the lower rack to continue to move upward and rotate the lower socket wrench until the lower jackscrew has been tightened with a force equal to that applied to the upper jackscrew.

As seen in Figure 3, door machine 15 has a pair of upper and lower movable hooks 105 in the form of levers having pivotal connection with bumpers 35 at points 106. One end of each of bumpers 35 is connected by a pin 108 to a bracket 109 attached to the door machine housing 38, the other end of each of the bumpers being connected to a spring pressed pin 115 also supported by the door machine housing, to help cushion any shock of contact between bumpers 35 and hook plates 33 of the coke oven door. The upper and lower hooks 105 are pivotally connected at points 111 for synchronous movement by means of a rod 107 having a turnbuckle 110 to adjust the length of the rod and the position of the hooks 105 with respect to each other. Another rod 112 is pivoted at one end to the hook portion of upper hook lever 105 at point 113 and is attached at its opposite end to pivot pin 118. Rod 112 also has a turnbuckle 114 to adjust its length.

A pair of upper and a pair of lower fingers 123 are provided, each pair being connected to a bar 124 near the opposite ends thereof. Bar 124 is supported by arms 125 through pivotal connections at points 126. At the opposite ends of arms 125, as noted in Figure 4, are pivot pins 127 connected to door machine housing 38 by means of brackets 128. Bar 125 has a clevis pin 131 intermediate its ends, the clevis pin being connected to pivot pin 118.

Pivot pin 118 having rod 112 and bar 124 connected thereto is in turn attached to a bell crank 117. Bell crank 117 is mounted to oscillate

about pin 119 and carries a roller 120 bearing against cam member 103 as it reciprocates up and down in response to the movement of piston rod 93 and guided cross head 95. Bell crank 117 operates in accordance with the movements of roller 120 over the surface of cam member 103. It is apparent that oscillation of the bell crank about pin 119 with consequent movement of pin 118 provides for synchronous actuation upwardly or downwardly of door hooks 105 and fingers 123. Hence, for example, in removal of a coke oven door, the fingers 123 rise and rotate the latch bars 23 of the door 18 out of the frame hooks 30 at just about the same time that hooks 105 of the door machine make contact with the hook plates 33 of the door. Turnbuckles 110 and 114 enable adjustment of the relative position of hooks 105 and the fingers 123 to provide the desired coordinated movement therebetween for contacting in proper sequence the hook plates and latch bars of the door. It is noted that the hooks 105 are usually so adjusted through turnbuckle 114 on rod 112, in relation to cam 117 that hooks 105 will continue to rise a short distance after contact thereof with the door hook plates 33, thus raising the coke oven door slightly against the door frame before the door is retracted from the coke oven mouth.

The lower portion of the door machine 15 is balanced in relation to the ram or carrier 41 by means of a turnbuckle connection 135 pivotally connected at point 136 to ram 41, the other end being attached by means of pivot pin 134 to one end of a bell crank 132 connected to door machine housing 38 through pivot pin 133. A spring 139 maintained under compression and resting on member 140 attached to the door machine housing, is connected to the opposite end of bell crank 132 from pivot point 134 through rod 141 fixed at its upper end by means of nuts 142 to the top of spring 139, the other end of the rod having pivotal connection with bell crank 132 at point 143. This arrangement, as illustrated in Figure 11, is such that when the door machine is not in contact with a door in the coke oven mouth, the spring 139 urges rod 141 upwardly causing the bell crank 132 to oscillate clockwise principally about pivot point 134, but with some pivotal movement also about pin 133, urging the front edge 144 of the bell crank forward to the dotted line position indicated. Thus, when the door machine is out of contact with a door in the mouth of the coke oven, the lower portion 145 of the door machine is projected somewhat farther forward than the upper portion 146 thereof so that under these circumstances the door machine is not suspended in a perfectly vertical plane as indicated by position X, but is in a slightly inclined or tilted position as indicated by X' with the upper portion 146 somewhat behind the lower portion 145. The degree of tilt of the door machine may be regulated by expanding or contracting turnbuckle 135.

When the door machine 15 is moved forward toward a coke oven door for removal thereof, the lower portion 145 of the door machine makes contact first with the door, and as the upper portion 146 of the door machine engages the door on further forward movement of the ram 41, spring 139 will be opposed by such forward movement of the ram through turnbuckle 135, thus causing the bell crank 132 to turn in a counterclockwise direction chiefly about pivot point 133 to the full line position shown. On the other hand, when the door machine is re-

tracted outwardly away from the mouth of the oven, the upper portion 146 of the door machine will move away from the mouth of the coke oven first and as pin 136 on ram 41 continues to be further retracted, the resistance of the ram against spring 139 will gradually be removed allowing the spring through rod 141 to urge bell crank 132 from the full line position to the dotted line position shown in Figure 11. When the lower portion of the door machine is finally free from contact with the lower portion of the door frame the door machine once again is in the inclined position above described with the bottom portion 145 of the door machine advanced farther forward than the upper portion 146 thereof.

In complete operation of the door machine of the invention for removing and replacing a coke oven door from the mouth of a coke oven battery, door machine 15 is first spotted adjacent the door 18 and the door machine is moved forward toward it. On contact of bumpers 35 of the door machine with hook plates 33 of the door, socket wrenches 52 are brought into engagement with the squared heads 25 of the corresponding upper and lower jackscrews 24. If the socket wrenches are not in perfect alignment with the jackscrews, turnbuckle 46 may be either expanded or contracted so as to either raise or lower the door machine. This raising or lowering of the door machine through rotation of yoke 39 about pins 42 results in a raising or lowering of the socket wrenches 52 constituting a fine adjustment of the socket wrenches relative to the position of the jackscrews to enable proper engagement therewith. Should the pointed end of a jackscrew strike the side of the flared portion of a socket wrench 52, spring 60 will yield and allow socket wrench 52 to center on the jackscrew. The free rotational play or back lash between shaft 65 and gear 64 brought about through the arrangement of clutch jaws 66 and 67 respectively thereon, allows sufficient rotation of the socket wrench 52 onto the squared head 25 of the jackscrew for full engagement therewith. Hence, springs 60 in conjunction with the free rotational play afforded by the aforementioned clutch mechanism, permit substantially instant engagement between the socket wrenches and corresponding jackscrews.

Hydraulic pressure is then applied to the top of cylinder 92 to drive piston 91 and attached piston rod 93 and cross head 95 downwardly. Downward movement of the cross head carries both racks 77 in the same direction bringing about rotation of gears 70 which, through gears 64 and 61, in turn cause rotation of shafts 54, socket wrenches 52 and the engaged jackscrews in a clockwise direction for movement of the latch bars 23 toward the door and out of engagement with frame hooks 30. It is noted that the aforementioned back lash due to clutch jaws 66 and 67 will allow the piston to begin its initial downward stroke before meeting any resistance from the jackscrews. When both the upper and lower jackscrews on the coke oven door have been rotated sufficiently to loosen the latch bars from contact with the frame hooks, flat portions 79 of racks 77 come into engagement with the flat portions 78 of gears 70 and there is no further rotation of the socket wrenches 52. Figures 1, 3 and 6 show the door machine in this position. The major portion, say from 80 to 85%, of the piston stroke is taken up in rotating the socket wrenches and the engaged jackscrews.

The remainder of the downward stroke of the

piston in cylinder 92 carries cam member 103 downwardly from its position shown in Figure 3, resulting in movement of roller 120 in engagement therewith to the right and over the top of cam member 103. Under the circumstances, bell crank 117 oscillates about pin 119 in a counter-clockwise direction causing pivot pin 118 to move upwardly carrying rod 112 and bar 124 simultaneously in the same direction. Such movement of rod 112 first brings hooks 105 into engagement with hook plates 33 of the coke oven door while continued upward movement of rod 112 causes the engaged hooks to raise the door a short distance above its seat, say on the order of about one inch, to facilitate its removal from the coke oven mouth, the self-aligning socket wrench mechanisms of the door machine of the invention compensating for any relative movement between the jackscrews and socket wrenches during such upward movement of the door. Further, while the door is being thus raised vertically, it remains in contact with the door frame and tends to loosen any incrustations of carbonaceous material which may have been deposited along the sealing edges of the door and/or frame during carbonization. In this same period while the hooks 105 are making contact with hook plates 33 and raising the door slightly, fingers 123 mounted on bar 124 rise into contact with and rotate latch bars 23 in a clockwise direction, as seen in Figure 2, sufficiently away from the horizontal to clear the hooks 30 on the door frame. The door machine 15 with the door firmly grasped thereby is then retracted outwardly on ram 41 by a separate power means (not shown), the top portion of the door moving away from the door frame before the lower portion of the door breaks contact with the door frame so that the door is held balanced and suspended away from the door frame in a slightly inclined position from the vertical in the manner described above.

For replacing a coke oven door 18 in its frame in the mouth of the coke oven, ram 41 carrying the door machine 15 and the engaged door is moved forward until the door makes contact with the door frame. In so doing, through the arrangement of spring 139, bell crank 132 and turnbuckle 135 as described above, the lower portion of the door 18 engages the door frame first and as the ram continues to move forward slightly, the upper portion of the door then makes contact with the door frame. Hydraulic pressure is applied to the bottom of cylinder 92 causing piston 91 and attached piston rod 93 and cross head 95 with associated gear racks 77 to move upwardly. The first portion of upward travel of the piston brings roller 120 in contact with the underside of cam member 103, as seen in Figure 3, oscillating bell crank 117 in a clockwise direction and lowering rod 112 and bar 124. Such movement of the rod lowers the door 18 vertically into its seat in the door frame after which hooks 105 become disengaged from hook plates 33. During this period the lowering of bar 124 causes fingers 123 to move downwardly to rotate the latch bars 23 of the door downwardly in a counterclockwise direction, as seen in Figure 2, into a horizontal position in the hooks 30 on the door frame 17. The lowering of rod 112 and bar 124 is brought about largely by their weight and the weight of the associated parts.

As piston rod 93 and cross head 95 continue to move upwardly, the teeth 81 of end segments 77a

of racks 77 make contact with the teeth 69 of gears 70 to rotate the socket wrenches 52 and the engaged jackscrews in a counterclockwise direction to tighten the jackscrews and move latch bars 23 away from the door and into tight frictional engagement with frame hooks 30. Should the full tightening force be applied to one jackscrew before the other, the pinion 86 in conjunction with racks 77 functions in the manner above described, i. e. as a differential, in effecting equal tightening of the other jackscrew to insure a gas-tight seal between the door and its frame. After the piston reaches the top of the stroke the socket wrenches are disengaged from the jackscrews, following which the racks 77 return to a centered position with respect to each other by the action of springs 88. The door is now in gas-tight position in the coke oven mouth with the sealing edge 20 of the door tightly pressed against the door frame 17. The door machine 15 may then be retracted and another coking cycle commenced.

I claim:

1. A door machine for manipulating a coke oven door adapted to seat against a door frame, said door comprising a plurality of rotatable members and a plurality of latch bars each pivotally connected to said members respectively for rotation thereon into and out of engagement with hook members on said door frame; which comprises means for operating said rotatable members, means for rotating said latch bars, door engaging means, and a single actuating means interconnected with all of said foregoing means for coordinating the operation of said foregoing means in proper sequence to manipulate said door.

2. A coke oven door machine for manipulating a coke oven door adapted to seat against a stationary door frame, said door comprising a plurality of members each rotatable on a separate horizontal axis and a plurality of latch bars each pivotally connected to said members respectively for rotation thereon into and out of engagement with hook members on said door frame; which comprises socket wrenches for engaging said rotatable members, rack and pinion means arranged to operate said wrenches, means for rotating said latch bars, door engaging means, and a single actuating means interconnected with all of said foregoing means for automatically coordinating the operation of said foregoing means in proper sequence to manipulate said door.

3. A door machine for manipulating a coke oven door adapted to seat against a stationary door frame, said door comprising a plurality of members each rotatable on a separate horizontal axis and a plurality of latch bars each pivotally connected to said members respectively for rotation thereon into and out of engagement with hook members on said door frame; which comprises self-aligning socket wrenches for engaging said rotatable members, rack and pinion means constructed and arranged to rotate said wrenches through a system of gears, means for rotating said latch bars into and out of engagement with said hook members, door engaging means, and a single actuating means interconnected with all of said foregoing means for automatically coordinating the operation of said foregoing means in proper sequence to manipulate said door.

4. A coke oven door machine for grasping and suspending a coke oven door out of contact with

the mouth of a coke oven, said door being adapted to seat against a door frame and comprising a plurality of members each rotatable on a separate horizontal axis and a plurality of latch bars each pivotally connected to said members respectively for rotation thereon into and out of engagement with hook members on said door frame; which comprises self-aligning socket wrenches for engaging said rotatable members, rack and pinion means constructed and arranged to rotate said wrenches through a system of gears, means for rotating said latch bars into and out of engagement with said hook members, door engaging means, a spring pressed member adapted to urge the lower portion of said door machine against said door, and a single hydraulic actuating means interconnected with all of said foregoing means for automatically coordinating the operation of said foregoing means in proper sequence to manipulate said door.

5. A coke oven door machine for grasping and suspending a coke oven door in balanced position out of contact with the mouth of a coke oven, said door being adapted to seat against a stationary door frame and comprising a plurality of members each rotatable on a separate horizontal axis, and a plurality of latch bars each pivotally connected to said members respectively for rotation thereon into and out of engagement with hook members on said door frame; which comprises self-aligning socket wrenches for engaging said rotatable members, each of said wrenches including a driven shaft, a flared end portion for engaging said rotatable members, a spring mounted at one end in a hollow portion of said shaft and having its other end in contact with said flared end portion and a sleeve connecting said shaft with said flared portion for rotation thereof, said flared portion being angularly movable with respect to said sleeve and said sleeve being angularly movable with respect to said shaft; rack and pinion means constructed and arranged to rotate said shaft, means for rotating said latch bars into and out of engagement with said hook members, door engaging means, and a single actuating means interconnected with all of said foregoing means for automatically coordinating the operation of said foregoing means in proper sequence to manipulate said door.

6. A coke oven door machine for grasping and suspending a coke oven door in balanced position out of contact with the mouth of a coke oven, said door being adapted to seat against a stationary door frame and comprising a plurality of rotatable members with their axes in a horizontal plane and a plurality of latch bars pivotally connected to said members for rotation thereon into and out of engagement with hook members on said door frame; which comprises self-aligning socket wrenches for engaging said rotatable members, rack and pinion means comprising two racks each in contact with a single pinion and each in respective engagement with a system of gears arranged to cause rotation of said wrenches, said rack and pinion means being adapted to exert equal tightening force on said wrenches and rotatable members during replacement of a door in its frame and tightening of said latch bars in said hook members, means for rotating said latch bars into and out of engagement with said hook members, door engaging means, and a single actuating means interconnected with all of said foregoing means for automatically co-

ordinating the operation of said foregoing means in proper sequence to manipulate said door.

7. A door machine for manipulating a coke oven door adapted to seat against a door frame, said door comprising a plurality of members each rotatable on a separate horizontal axis, a plurality of latch bars each pivotally connected to said members respectively for rotation thereon into and out of engagement with hook members on said door frame and a plurality of hook plates; which comprises self-aligning socket wrenches for engaging said rotatable members, rack and pinion means constructed and arranged through a system of gears to rotate said wrenches, fingers for rotating said latch bars into and out of engagement with said hook members, hooks for engaging said hook plates, a cam operated member connected to said fingers and said hooks, and a single means interconnected with said rack and pinion means and said cam operated member for actuating and automatically coordinating the operation of said rack and pinion means and said member with associated fingers and hooks in proper sequence to manipulate said door.

8. A coke oven door machine for removing and replacing a coke oven door and maintaining it suspended in balanced position out of contact with the mouth of a coke oven for cleaning purposes, said door being adapted to seat against a door frame and comprising a plurality of members each rotatable on a separate horizontal axis, said members being located substantially in a vertical plane, a plurality of latch bars each pivotally connected to said members respectively for rotation thereon into and out of engagement with hook members on said door frame and a plurality of hook plates; which comprises self-aligning socket wrenches for engaging said rotatable members, rack and pinion means constructed and arranged through a system of gears to rotate said wrenches and exert equal tightening force thereon during replacement of a door in its frame and tightening of said latch bars in said hook members, a clutch mechanism arranged in conjunction with said system of gears to allow a measure of play between movement of said rack and pinion means and the thus actuated wrenches, fingers for rotating said latch bars into and out of engagement with said hook members, hooks for engaging said hook plates, a cam operated member interconnected with said fingers and hooks, a spring pressed member adapted to urge the lower portion of said door machine and door against said door frame, and a single hydraulic actuating means interconnected with said rack and pinion means and said cam operated member whereby, on actuation of said hydraulic means in one direction to remove said door, said rotatable members rotate in a direction to disengage said latch bars from said frame hooks, and thereupon said hooks engage said hook plates and said fingers rotate said latch bars out of said frame hooks, and on actuation of said hydraulic means in the opposite direction to replace said door against its door frame, the opposite sequence of operations takes place.

9. A coke oven door machine as defined in claim 8 wherein the door machine is supported and balanced from points near its top and bottom, on a carrier adapted to retract said machine and an engaged door away from the coke oven mouth for cleaning and to move said machine and door toward the mouth of the coke oven for replacement of the door against its frame, said door machine including a mechanism to raise and

lower said machine for properly adjusting the position of said socket wrenches relative to said rotatable members; said spring pressed member being in association with the bottom point of balance of the machine on said carrier and urging the lower portion of said door machine against the lower portion of said door whereby, when the door machine and an engaged door are suspended out of contact with the coke oven mouth, said machine and door are in a plane somewhat inclined from the vertical with the lower portion of said machine and door farther forward than the upper portion thereof; and said cam operated member and interconnected fingers and hooks being so designed that said door moves upward a short distance against its door frame just prior to retraction of the door from the coke oven mouth, and moves downward against the frame and into its seat just after the door makes contact with its frame during replacement of the door.

10. A coke oven door machine for removing and replacing a coke oven door and maintaining it in balanced position out of contact with the mouth of a coke oven, said door being adapted to seat against a stationary door frame and comprising a plurality of members each rotatable on a separate horizontal axis, said members being located substantially in a vertical plane, and a plurality of latch bars each pivotally connected to said members respectively for rotation thereon into and out of engagement with hook members on said door frame; which comprises self-aligning socket wrenches for engaging said rotatable members, each of said wrenches including a driven shaft, a flared portion for engaging said rotatable members, said flared portion having a closure member at one end thereof, a spring mounted at one end in a hollow portion of said shaft and having its other end in contact with said closure member and a sleeve connecting said driven shaft with said flared portion for rotation thereof, said flared portion being angularly movable with respect to said sleeve and said sleeve being angularly movable with respect to said shaft; rack and pinion means comprising two racks each in contact with a single pinion and each in respective engagement with a system of gears arranged to cause rotation of said wrenches on movement of said racks, said rack and pinion means being adapted to exert equal tightening force on said wrenches and rotatable members during replacement of a door in its frame and tightening of said latch bars in said hook members, means for moving said latch bars into and out of engagement with said hook members, door engaging means, and a single hydraulic actuating means interconnected with all of said foregoing means for automatically coordinating the operation of said foregoing means in proper sequence to manipulate said door.

11. A coke oven door machine for removing and replacing a coke oven door and maintaining it suspended in balanced position out of contact with the mouth of a coke oven for cleaning purposes, said door being adapted to seat against a door frame and comprising upper and lower parallel rotatable members located substantially in a vertical plane, a pair of latch bars each pivotally connected to said upper and lower members respectively for rotation thereon into and out of engagement with hook members on said door frame and upper and lower hook plates; which comprises upper and lower self-aligning socket wrenches each including a hollow driven

shaft, a flared portion having rounded outwardly extending sides for engaging said rotatable members, said flared portion having a closure member at one end thereof, a spring mounted at one end in a hollow portion of said shaft and having its other end in contact with said closure member, the hollow end of said shaft having rounded outwardly extending sides, a sleeve in frictional contact with the outwardly extending sides of said shaft and said flared portion for rotation thereof in unison with said shaft, said flared portion being angularly movable with respect to said sleeve and said sleeve being angularly movable with respect to said shaft, thereby permitting longitudinal and lateral movement of said wrenches in relation to said rotatable members; rack and pinion means comprising two racks each in contact with a single pinion and each in respective engagement with a system of gears arranged to cause rotation of said wrenches on movement of said racks, said rack and pinion means being adapted to exert equal tightening force on said rotatable members during replacement of a door in its frame and tightening of said latch bars in said hook members, a clutch mechanism in conjunction with said system of gears to allow a measure of play between movement of said racks and the thus actuated wrenches, fingers for rotating said latch bars into and out of engagement with said hook members, hooks for engaging said hook plates, a member interconnected with said fingers and hooks, a cam element for operating said member, a spring pressed member adapted to urge the lower portion of said door machine against said door and a single hydraulic actuating means attached to said rack and pinion means and said cam element whereby, on actuation of said hydraulic means in one direction to remove said door, said rotatable members rotate in a direction to disengage said latch bars from said hook members, and thereupon said hooks engage said hook plates and said fingers rotate said latch bars out of said hook members, and on actuation of said hydraulic means in the opposite direction to replace said door against its door frame, the opposite sequence of operations takes place.

12. In a coke oven door machine of the type described, a self-aligning socket wrench mechanism for rotating a spindle of a coke oven door, comprising a driven shaft, a flared end portion for engaging said spindle, said flared portion having a closure member at one end thereof, a spring mounted at one end in a hollow portion of said shaft and having its other end in contact with said closure member and a sleeve connecting said driven shaft with said flared portion for rotation thereof, said flared portion being angularly movable with respect to said sleeve and said sleeve being angularly movable with respect to said shaft, whereby said flared portion is adapted to properly engage and rotate a corresponding spindle even if said flared portion and said spindle are out of alignment.

13. In a coke oven door machine of the type described, a self-aligning socket wrench mechanism as defined in claim 12 having a driving shaft in operative engagement with said driven shaft and a clutch mechanism on said driving shaft constructed and arranged to impart a measure of play between said driving and driven shafts.

14. In a coke oven door machine of the type described, a self-aligning socket wrench mechanism for rotating the jackscrews of a coke oven

door for manipulation thereof, which comprises a driven shaft having a hollow portion in one end, the hollow end of said shaft having rounded outwardly extending side portions, a sleeve mounted on said shaft with the inner surface of one end of said sleeve in frictional contact with said rounded side portions, a flared socket wrench having rounded outwardly extending side portions and adapted to engage the end of one of said jackscrews, a closure member in contact with the other end of said socket wrench, the rounded side portions of said socket wrench being in frictional contact with the inner surface of the other end of said sleeve, a compression spring having one end mounted in the hollow portion of said shaft and the other end in contact with said closure member, said socket wrench and said sleeve being fixed for rotation in unison with said shaft, and said socket wrench being adapted to move angularly with respect to said sleeve and said sleeve being in turn adapted to move angularly with respect to said shaft, thereby permitting longitudinal and lateral movement of said wrench in relation to a corresponding jackscrew for proper engagement and rotation thereof even if out of alignment with said wrench.

15. In a coke oven door machine of the type described, a self-aligning socket wrench mechanism as defined in claim 15 including an outwardly extending shoulder at the end of said sleeve in contact with said shaft, a stop member adjacent thereto, an inwardly extending shoulder at the opposite end of said sleeve and a shoulder on said closure member, whereby, when said socket wrench is in free position out of contact with a jackscrew, said spring urges said sleeve forward so that said outwardly extending shoulder at one end of said sleeve is in engagement with said stop member and said inwardly extending shoulder is in contact with the shoulder on said closure member, thus maintaining the socket wrench mechanism substantially perpendicular to the face of the coke oven door prior to engagement thereof.

16. In a coke oven door machine of the type described, a self-aligning socket wrench mechanism as defined in claim 14 for rotating the jackscrews of a coke oven door for removing and replacing said door, having a first gear fixed to the other end of said driven shaft from the hollow portion thereof, a driving shaft parallel to said driven shaft, a second gear loosely mounted on said driving shaft near one end thereof and in engagement with said first gear, jaws on said driving shaft and interlocking jaws on said second gear, said jaws being respectively spaced so as to allow a degree of free rotation between said driving shaft and said second gear and between said driving shaft and said socket wrench, said spring and said degree of free rotation permitting said socket wrench to adapt itself for substantially instant engagement with the end of a corresponding jackscrew.

17. In a coke oven door machine of the type described having upper and lower socket wrenches for rotating the upper and lower spindles of a coke oven door, a device for applying equal tightening force to said socket wrenches and spindles when in operative relationship, which comprises two parallel racks each in contact with a single pinion and each in respective engagement with a system of gears arranged to cause rotation of said socket wrenches, whereby on movement of said racks and associated pinion in a direction to effect tightening of said spindles and socket

wrenches, said pinion acts as a differential to exert equal tightening force on both spindles.

18. In a coke oven door machine of the type described having upper and lower socket wrenches for rotating the upper and lower jackscrews of a coke oven door, a device for applying equal tightening force to said socket wrenches and jackscrews when in operative relationship, which comprises two parallel racks each being encased at one end in a housing having sliding engagement with said racks, a pinion in said housing in engagement with said racks, springs in said housing each in contact with the respective ends of said racks urging them away and tending to maintain the racks in a centered position with respect to each other, the opposite end of each of said racks having engagement with a system of gears arranged to cause rotation of said socket wrenches, whereby on movement of the racks and pinion in a direction to effect tightening of said jackscrews and socket wrenches, said pinion acts as a differential and commences to rotate with respect to said racks after one jackscrew has been completely tightened and until the same tightening force has been applied to the other jackscrew.

19. In combination in a coke oven door machine of the type described, upper and lower self-aligning socket wrenches for rotating the upper and lower spindles of a coke oven door, each comprising a driven shaft, a flared portion for engaging said spindles, said flared portion having a closure member at one end thereof, a spring mounted at one end in a hollow portion of said shaft and having its other end in contact with said closure member and a sleeve connecting said driven shaft with said flared portion for rotation thereof, said flared portion being angularly movable with respect to said sleeve and said sleeve being angularly movable with respect to said shaft, whereby said flared portion is adapted to properly engage and rotate a corresponding spindle even if they are out of alignment, a driving shaft in operative engagement with said driven shaft and a clutch mechanism on said driving shaft to permit a measure of play between said driving and driven shafts; and a device for applying equal tightening force to said socket wrenches and spindles when in operative relationship, which comprises two parallel racks each in contact with a single pinion and each in operative engagement with one of said driving shafts to cause rotation of said socket wrenches, whereby on movement of said racks and associated pinion in a direction to effect tightening of said spindles and socket wrenches, said pinion acts as a differential to exert equal tightening force on both spindles.

20. In combination in a coke oven door machine of the type described, upper and lower self-aligning socket wrench mechanisms as defined in claim 15 for rotating the upper and lower jackscrews of a coke oven door for removing and replacing said door, said mechanisms having a first gear fixed to the other end of said driven shaft from the hollow portion thereof, a driving shaft parallel to said driven shaft, a second gear loosely mounted on said driving shaft near one end thereof and in engagement with said first gear, jaws on said driving shaft and interlocking jaws on said second gear, said jaws being respectively spaced so as to allow a degree of free rotation between said driving shaft and said second gear, and a third gear mounted on said driving shaft near the end opposite said second

gear; and a device for applying equal tightening force to said socket wrenches and jackscrews when in operative relationship which comprises a pair of parallel racks each in contact at their opposite ends with said third gear, the other ends of said racks being encased in a housing having sliding engagement with said racks, a pinion in said housing in engagement with said racks, springs in said housing in contact with the respective ends of said racks urging them away and tending to maintain the racks in a centered position, said racks and pinion mechanism being adapted to rotate said socket wrenches by reciprocating movement of said mechanism, whereby on movement of the racks and pinion in a direction to effect tightening of said jackscrews and socket wrenches, said pinion acts as a differential and commences to rotate with respect to said racks after one jackscrew has been completely tightened and until the same tightening force has been applied to the other jackscrew.

21. In a coke oven door machine of the type described, upper and lower interconnected hooks for engaging the hook plates of a coke oven door, an arm pivotally engaged at one end thereof to one of said hooks and at the other end to a pivoted bell crank, said bell crank having a roller mounted thereon, a pair of upper and lower fingers adapted to make contact with the latch bars of said door, said fingers being mounted on a bar pivotally connected at a point intermediate its ends to said bell crank, and an actuating mechanism having a cam member in contact with said roller, whereby on actuation of said cam member, the associated roller moving in response thereto causes oscillation of said bell crank and synchronized actuation of said hooks and fingers for manipulation of said door.

22. In the device defined in claim 19, interconnected upper and lower hooks for engaging the door, upper and lower fingers for contacting and rotating latch bars pivotally mounted on the spindles of the door, said hooks operating in conjunction with said fingers by means of a cam and roller mechanism, and a single means connected to said racks and to said cam for actuating and coordinating the operation of said racks and associated pinion, and said cam and roller mechanism with associated hooks and fingers, in proper sequence for removing or replacing a coke oven door.

23. Apparatus for removing and replacing a coke oven door in its frame in the mouth of a coke oven, said door comprising upper and lower jackscrews adapted to rotate about a horizontal axis, a latch bar pivotally mounted on each of said jackscrews for rotation thereon into and out of engagement with hook members on said door frame and upper and lower hook plates; which comprises a support, a carrier mounted on said support for movement toward and away from the coke oven mouth, a lever supported by said carrier, a door machine pivotally suspended in a housing from a point intermediate the ends of said lever, means for raising and lowering the door machine housing and door machine for proper adjustment of the latter relative to the jackscrews on said door, said door machine comprising upper and lower self-aligning socket wrenches for engaging said jackscrews, a system of gears associated with each of said socket wrenches, a pair of racks each engaged at their opposite ends with one gear of said respective gear systems, each of said racks having a flat

portion near one end thereof for contact with a flat portion on said one gear, the other ends of said racks being encased in a housing having sliding engagement with said racks, a pinion in said housing in engagement with said racks, springs in said housing in contact with the respective ends of said racks urging them away and tending to maintain the racks in a centered position with respect to each other, said racks and pinion mechanism being adapted to rotate said socket wrenches by reciprocating movement of said mechanism and said pinion acting as a differential to apply equal tightening force to the socket wrenches and jackscrews on movement of the racks and pinion in a direction to effect tightening of said jackscrews, fingers for rotating said latch bars into and out of engagement with said hook members, upper and lower hooks for engaging said hook plates, a member interconnected with said fingers and hooks, a cam for operating said member, hydraulic actuating means attached to said racks and pinion housing and said cam, a spring pressed member urging the lower portion of said door machine towards the lower portion of said door, said spring pressed member including a compression spring and a rod connected at one end to said spring and at the other end to a bell crank associated with said carrier, whereby, on movement of said door machine and an engaged door away from the door frame, the top portion of the door is retracted from the door frame before the bottom portion thereof and when the door is replaced against the door frame, the bottom portion of the door makes contact with the bottom portion of the door frame before the top portion of the door comes into contact with the door frame, operation of said actuating means in one direction for removal of said door causing movement of said racks in the same direction to rotate said socket wrenches and the engaged jackscrews in a direction to disengage said latch bars from said hook members, followed by engagement of said hooks with said hook plates and contact of said fingers with said latch bars and rotation thereof out of said frame hook members, the opposite sequence of operations taking place during replacement of said door against said door frame.

24. Apparatus for removing and replacing a coke oven door in its frame in the mouth of a coke oven, said door comprising upper and lower parallel rotatable jackscrews having their axes in a horizontal plane, a pair of latch bars each pivotally mounted on one of said jackscrews for rotation thereon into and out of engagement with hook members on said door frame and upper and lower hook plates; which comprises a support, a carrier mounted on said support for movement toward and away from the coke oven mouth, a lever in the form of a yoke having an open end and a closed end, said lever being in a substantially horizontal plane and being pivotally supported at its open end by said carrier from a position near the upper portion thereof, a door machine pivotally suspended in a housing from a point intermediate the ends of said lever, a turnbuckle having one end connected to a bracket on said housing and the other end pivotally engaged to the closed end of said lever, said turnbuckle being adapted to rotate said lever about its point of connection with said carrier to thereby raise and lower the door machine housing and door machine for proper adjustment of the latter relative to the jackscrews on said

door, said door machine comprising self-aligning socket wrenches for engaging said rotatable jackscrews, rack and pinion means constructed and arranged through a system of gears to rotate said wrenches and exert equal tightening force thereon during replacement of a door in its frame and tightening of said latch bars in said hook members, a clutch mechanism arranged in conjunction with said system of gears to allow a measure of play between movement of said rack and pinion means and the thus actuated wrenches, upper and lower interconnected hooks for engaging the hook plates of said door, an arm pivotally engaged at one end thereof to one of said hooks and at the other end to a pivoted bell crank, said bell crank having a roller mounted thereon, a pair of upper and lower fingers adapted to make contact with the latch bars of said door, said fingers being mounted on a bar pivotally connected at a point intermediate its ends to said bell crank, a hydraulic cylinder having a piston, a rod connected thereto and a cross head attached to said rod, said cross head being connected to said rack and pinion means and to a cam member in contact with the roller on said bell crank, a second pivoted bell crank connected at one end to the lower portion of said carrier and at the other end to a compression spring by means of a rod, said spring urging the lower portion of said door machine toward the door, whereby on movement of said door machine and an engaged door away from the door frame, the top portion of the door is retracted from the door frame before the bottom portion thereof and when the door is replaced against the door frame, the bottom portion of the door makes contact with the bottom portion of the door frame before the top portion of the door comes into contact with the door frame, actuation of the piston rod and attached cross head in one direction for removal of said door causing movement of said rack and pinion means in the same direction to rotate said socket wrenches and the engaged jackscrews in a direction to disengage said latch bars from said hook members, followed by engagement of said hooks with said hook plates, contact of said fingers with said latch bars and rotation thereof out of said frame hook members, and a slight raising of the door above its seat, the opposite sequence of operations taking place during replacement of said door against said door frame.

25. In a coke oven door machine of the type described, a self-aligning socket wrench mechanism for rotating a spindle of a coke oven door, comprising a driven shaft, a flared end portion for engaging said spindle, a resilient member mounted at one end in a hollow portion of said shaft and having its other end in contact with said flared end portion and a sleeve connecting said driven shaft with said flared portion for rotation thereof, said flared portion being angularly movable with respect to said sleeve and said sleeve being angularly movable with respect to said shaft.
